FURNITURE ANTISKID DEVICE

Henry W. Hauser, Wauwatosa, Wis., assignor to
 Jonto Products Incorporated, Wauwatosa, Wis.,
 a corporation of Wisconsin

Application March 22, 1948, Serial No. 16,371

6 Claims. (Cl. 45—137)

1

The present invention relates generally to improvements in the art of retaining furniture in preselected position, and relates more particularly to improvements in the construction and operation of floor-engaging antiskid devices adapted to be utilized with diverse articles of furniture.

A primary object of the present invention is to provide an improved furniture antiskid device which is extremely simple, compact and durable in construction, which may be readily manufactured at low cost, and which is moreover highly efficient in operation.

Various types of devices for preventing undesirable misplacement of furniture and resultant marring of the furniture or of adjacent walls have heretofore been proposed. Some of these prior devices merely assumed the form of cup-shaped receiving members, either loosely associated with the floor or attached thereto by means of screws or the like, and adapted to loosely receive the legs of the furniture. However, it has been found that these devices were not entirely satisfactory since they did not effectively retain the furniture in position unless they were anchored securely to the floor, thus resulting in undesirable marring of the floor and also restricting use to heavy article of furniture which are not intended for periodic rearrangement. Another type of device heretofore proposed consisted of an elongated flat and rigid plate-like member having one end thereof adapted to engage the wall near the floor and with a recess formed in the opposite end for loosely receiving a leg of furniture to positively space the same from the wall. These devices, however, have also proved objectionable in that they were unsightly, interfered with cleaning, and were very restricted in application, being useful only in instances wherein the article of furniture was to be located near a wall and in alignment therewith. Still other devices have been proposed which were directly rigidly attachable to the legs of the furniture, but such devices obviously necessitated undesirable marring of the furniture and became an integral part thereof and also did not effectively eliminate displacement of the furniture to which they were applied.

It is, therefore, a more specific object of my present invention to provide an improved furniture antiskid device which obviates the disadvantages and objectionable features of prior structures intended for like purpose.

Another specific object of this invention is to provide an improved device for retaining furni-

2

ture or the like in a preselected position, and which may be readily applied and effectively utilized with any article of furniture having legs without necessitating attachment thereto.

Another specific object of the invention is to provide an improved furniture antiskid device which may be quickly and easily applied to diverse articles of furniture by a novice without detracting from the appearance thereof and without danger of marring either the furniture or the floor.

Another specific object of my invention is to provide an improved unitary furniture antiskid device which may be readily manufactured of available sheet material with the aid of punches and dies, and which may be effectively utilized to retain diverse articles of furniture at any desired locality within a room.

Still another specific object of my present invention is to provide an improved furniture antiskid device which is neat in appearance, which is exceedingly compact and does not interfere with cleaning, and which may be quickly loosely applied to the legs of furniture to retain the same in a preselected position.

An additional specific object of the present invention is to provide an improved antiskid device for furniture comprising, a floor-engaging socket adapted to loosely receive the leg of an article of furniture, a floor gripping pad disposed remote from the socket, and a resilient connection between the socket and pad adapted to be stressed so as to apply gripping pressure to the pad when a furniture leg bears upon the socket.

These and other specific objects and advantages of the improvement will be apparent from the following detailed description.

A clear conception of the several features constituting my present invention, and of the mode of constructing, applying and of utilizing furniture antiskid devices embodying the improvements, may be had by referring to the drawing accompanying and forming a part of this specification wherein like reference characters designate the same or similar parts in the various views.

Fig. 1 is a side view of a furniture antiskid device constructed in accordance with my invention;

Fig. 2 is a top view of the improved device; and

Fig. 3 is a front and side perspective view of the device, showing the same applied to a leg of a chair or the like and in active floor-gripping condition.

While the invention has been shown and described herein as embodied in a specific form of the device especially adapted for application to and utilization with the rear legs of a chair, it is not my desire or intent to thereby unnecessarily restrict the scope or utility of the improved features.

Referring to the drawing, the improved furniture antiskid device shown therein as embodying the invention comprises, in general, a floor-engaging socket 6 normally rearwardly inclined relative to the floor, illustrated by the numeral 5 in Fig. 1; a compressible floor-gripping pad 7 disposed remote from and rearwardly of the socket 6; and an inverted U-shaped leaf spring 8 having one leg 9 thereof formed integral with the upper rear end of the socket 6 and the other leg 10 coacting with the gripping pad 7 and adapted to be stressed so as to compress and apply gripping pressure to the pad 7 when a 20 furniture leg 11 bears upon the socket 6.

To provide a unitary assemblage, the floor-engaging leg-receiving socket 6 and the integral inverted U-shaped spring 8 may be formed of a single piece of sheet-metal or the like with the aid of punches and dies, and the compressible floor gripping pad 7 may be formed of rubber molded directly to the lower end of the leg 10. The inverted U-shaped spring 8 should, of course, be resilient but must also be sufficiently rigid so as to normally maintain the socket 6 in an inclined position relative to the floor 5 until pressure is placed on the socket 6 through the leg 11 received thereby. The socket 6 is preferably cup-shaped with the bounding side walls 12 being formed by either drawing the metal along the edge portion upwardly or by forming upturned flanges with the aid of punches and dies, and the compressible gripping pad may be provided with transverse grooves 13 in the lower floor engaging face thereof to provide for more effective gripping action. The inclination of the leg receiving socket 6 may, of course, be varied depending upon the resilience of the connecting spring 8 and the weight of the article to be received by the socket, and the generally U-shaped spring 8 may likewise be varied considerably but should provide a connection between the socket 6 and the gripping pad 13 adapted to be stressed upon application of weight to the socket 6 so as to compress and apply gripping pressure to the pad 7.

In actual use of the device in positioning a chair, one of the improved devices is utilized with each of the rear legs 11 of the chair, and it is merely necessary to lift the chair so that the rear legs 11 are off of the ground and then place each leg within the socket 6 of one of the improved devices, the gripping pad 7 being located rearwardly of the chair. With the legs 11 of the chair received by the socket 6 of the improved antiskid device, the socket 6 is still disposed at a slight angle to the floor by the rigidity of the leaf spring 8; and when a person sits on the chair, the socket 6 will be forced toward the floor 5 and approximately flush therewith thereby causing the spring 8 to be stressed so as to compress and apply gripping pressure to the pad 7 through the rear spring leg 10 to prevent skidding or displacement of the chair.

From the foregoing detailed description, it is apparent that my present invention provides an improved furniture antiskid device which is extremely simple, durable and compact in construction and which is moreover highly efficient in actual use. The improved devices may be ef-

fectively utilized with any articles of furniture having legs which are receivable in the inclined sockets; and while particular reference has been made to use of the improved devices with a chair, such devices have been successfully utilized to retain davenport, tables, beds and other articles of furniture in preselected positions. The improved antiskid device may obviously be quickly and easily applied to the legs 11 of the desired articles of furniture without necessity of anchoring the same to the floor 5 and without need for marring the furniture by attaching the same thereto and these devices may also be readily removed at any time without the aid of any tools. Since the furniture legs loosely engage these devices and since the devices are not anchored to the floor, the furniture may be moved from time to time and re-positioned and the application of the improved device is highly flexible and does not necessitate positioning the furniture near the wall of the room. The improved antiskid devices are extremely compact and do not interfere with cleaning and vacuuming of the floor and these devices likewise do not detract from the appearance of the furniture to which they are applied. The socket 6 and spring 8 may, as hereinabove set forth, be readily manufactured at low cost of available materials with the aid of punches and dies in an obvious manner and the floor gripping pads 7 may be molded directly to the leg 10 of the spring 8. These devices effectively prevent furniture displacement and have, in fact, proven highly successful and satisfactory in actual use.

It should be understood that it is not desired or intended to limit this invention to the exact details of construction or to the precise mode of use herein shown and described for various modifications within the scope of the appended claims may occur to persons skilled in the art to which this invention pertains.

I claim:

1. An antiskid device for furniture comprising, a floor-engaging socket adapted to loosely receive the leg of an article of furniture, said socket being normally inclined relative to the floor, a floor gripping pad disposed remote from said socket, and a connection between the upper end of said inclined socket and said pad adapted to transmit gripping pressure to said pad when a furniture leg bears upon said socket.

2. An antiskid device for furniture comprising, a floor-engaging socket adapted to loosely receive the leg of an article of furniture, said socket being normally inclined relative to the floor, a floor gripping pad disposed remote from said socket, and a leaf spring connection between said socket and pad adapted to be stressed so as to apply gripping pressure to the pad when a furniture leg bears upon said socket.

3. An antiskid device for furniture comprising, a floor-engaging socket adapted to loosely receive the leg of an article of furniture, said socket being normally inclined relative to the floor, a floor gripping pad disposed remote from said socket, and a resilient connection between said socket and pad adapted to be stressed so as to apply gripping pressure to the pad when a furniture leg bears upon said socket.

4. An antiskid device for furniture comprising, a floor-engaging socket adapted to loosely receive the leg of an article of furniture, said socket being normally inclined relative to the floor, a floor gripping pad disposed remote from said socket, and an inverted U-shaped leaf spring having one leg coacting with said socket and the

other leg coacting with said pad and adapted to be stressed so as to apply gripping pressure to the pad when a furniture leg bears upon said socket.

5. An antiskid device for furniture comprising, a floor-engaging socket adapted to loosely receive the leg of an article of furniture, said socket being normally inclined relative to the floor, a floor gripping pad disposed remote from said socket, and an inverted U-shaped leaf spring having one leg formed integral with the upper end of said inclined socket and the other leg coacting with said pad and adapted to be stressed so as to apply gripping pressure to the pad when a furniture leg bears upon said socket.

6. An antiskid device for furniture comprising, a floor-engaging member adapted to receive the leg of an article of furniture, said member being normally inclined relative to the floor, a floor

gripping pad disposed remote from said inclined member, and a connection between the upper end of said inclined member and said pad adapted to transmit gripping pressure to said pad when a furniture leg bears upon said member.
